UNITED STATES PATENT OFFICE.

HENRY J. ASMUS, OF ROCHESTER, NEW YORK, ASSIGNEE, BY DIRECT AND MESNE ASSIGNMENTS, TO UNITED SHOE MACHINERY COMPANY, OF PATERSON, NEW JERSEY, A CORPORATION OF NEW JERSEY.

MACHINE FOR USE IN THE MANUFACTURE OF FOOTWEAR.

1,160,968.

Specification of Letters Patent. Patented Nov. 16, 1915.

Application filed December 26, 1913. Serial No. 808,873.

To all whom it may concern:

Be it known that I, HENRY J. ASMUS, of Rochester, in the county of Monroe and State of New York, have invented certain improvements in Machines for Use in the Manufacture of Footwear, which improvements are fully set forth in the following specification and shown in the accompanying drawings.

10 The present invention relates to the manufacture of footwear and to a machine used in such manufacture, and an object of the invention is to form the seats and toes of footwear of the type in which the upper is turned inwardly, so as to eliminate objectionable creases and obtain a shoe which is neater in appearance and has more symmetrical lines than at present manufactured.

To these and other ends the invention 20 consists in certain parts and combinations of parts all of which will be hereinafter described, the novel features being pointed out in the appended claims.

In the drawings: Figure 1 is a top view 25 of an illustrative machine embodying the present invention, parts of the casing being shown in section so as to illustrate the molding devices; Fig. 2 is a vertical section on the line *a*—*a*, Fig. 1; Fig. 3 is a perspective view of one of the molding members; Fig. 4 is a vertical section on the line *b*—*b*, Fig. 1, showing the shoe out of engagement with the molding means; Fig. 5 is a view similar to Fig. 4 with parts broken away to show 35 the shoe engaging the molding means; Figs. 6 and 7 are enlarged detail views showing the shoe respectively engaged with and disengaged from the molding means; Figs. 8 and 9 are two detail side views of 40 the toe of a McKay shoe before and after being operated upon by the machine forming the subject matter of this invention, and Fig. 10 is a front view of the toe of a McKay shoe.

45 With that type of footwear in which the upper is turned inwardly at its lower edge as, for instance, the "McKay" shoe, the "welt" shoe and the "turned" shoe, difficulties are experienced during the manufac-

ture thereof, in eliminating the creases at 50 the toes and in properly shaping the seat, due to the inward-turning of the upper. Prior to this invention, it has been customary to iron out the creases by a stationary iron over which the vamp is moved back 55 and forth while secured upon a last. With this arrangement, only that portion above the edge of the sole or bend in the upper materials is smoothed out and this is done in a more or less defective way, depending 60 upon the skill of the operative. By the use of the illustrated embodiment of the present invention the upper materials on both sides of the sole edge line are smoothed out and the whole toe or the whole heel of the shoe 65 after it has been lasted is molded simultaneously, and is also preferably heated, the mold engaging not only the upper above the sole edge line or bend in the upper materials, but also the bend at the sole edge line and a 70 portion of the turned or under-lapping stock of the upper so that a neat curve, extending about the sole edge, is formed.

A machine which I have found desirable for carrying out the above method comprises 75 a frame preferably formed of a horizontally-extending portion 1 and an upright portion 2 at one end of the horizontally-extending portion. Upon this upright portion may be arranged a holding means comprising preferably two molding members or devices 3 which, when associated together, are adapted to conform to the heel or to the toe of the footwear. In this instance, a machine is shown as designed for shaping the 80 toe portion of the footwear, but it is apparent that the machine may be readily 85 changed to shape also the heel portion.

The molding devices herein shown, which are more particularly adapted for the toe of 90 a McKay shoe or a welt shoe after it has been lasted, each have a curved wall 4 which conforms to one side of the toe from a point at the median line of the shoe to a point beyond the box of the shoe and above the bend 95 or sole edge line of the upper. Each molding device is preferably formed of metal and has a concaved curved portion 5 for en-

gaging the bend or sole edge line of the upper and a portion 6 substantially at right angles to the portion 4 for engaging the inwardly-turned or underlapping stock. Any suitable means may be employed for supporting these molding devices so that they will have a freedom of movement permitting them to conform to the shape of the shoe. In this instance, these molding devices are loosely mounted so that they may be termed to "float" and, to this end, each has ears 7 pivoted at 8 to a link 9 which in turn is pivoted at 10 to the upright 2. The proximate ends of the dies or molds each have flat portions 11 abutting when the dies are not engaged by the shoe, and also have portions 12 which serve as fulcrums on which the dies turn or rock relatively to each other for conforming to the end of the shoe, said portions 12 being at acute angles to the portions 11. From the abutting portions 11, the flange portions 6 incline upwardly toward the outer ends of the molding devices at a slight angle to the plane of movement of the molding devices, so that the flanges may conform to the plane of the sole of the shoe when the latter is supported in a horizontal position on a last. The dies are normally held in the position shown in Fig. 7 so that their portions 11 abut, yielding means being employed for this purpose. In this instance, a yoked member 13 has rollers 14 at the ends of its two arms for engagement with the inner faces 15 of the two die members 3, said yoked member exerting pressure on the proximate ends of the dies by means of a coiled spring 16 interposed between the upright portion 2 of the casing and the yoked member.

In order to guide the dies 3 in a single plane of operation so that they will have no vertical movement, a guiding means is employed comprising preferably two walls 17 and 18 arranged in parallel relation and forming a chamber between them, the yoke 13 also being guided between said walls. The upper guide wall 17 may be a removable top wall for the upright portion 2 of the frame of the machine and may be recessed or cut away to the general curve of the dies or molding devices. The depending front edge of the cut away or recessed portion may be engaged by the forward ends of the flanged portions 6 so as to limit the movements of the molding devices under the action of the spring 16. The lower guide wall 18 may be employed for heating the dies or molding devices 3 to the desired temperature suitable for shrinking or contracting the leather by conduction, and to this end an electrical heating coil 19 is arranged below and in contact with the wall 18, said coil being curved to correspond to the general curve of the two dies, a non-conducting covering 20 preferably inclosing the heat-

ing coil between said wall 18 and a curved wall 21 of a pocket 22 which is formed in the framed portion 2 below the molding dies in order that the work on the work support may be presented to such dies.

The work support is preferably in the form of a last 23 fitted by means of its jack pin hole to a stem 24 in an inverted position, said stem preferably having screw-threaded engagement with the carriage 25 in order that the last may be raised and lowered on the carriage to locate the plane of the toe bottom parallel with the faces 6 of the dies 3. The carriage 25 is preferably movable in horizontal ways or guides 26 formed on the horizontal portion 1 of the frame and extending in a line parallel with the median line through the molding devices in order that the last may be moved toward and from the molding devices. The means for moving this last or work support preferably embodies a cam 27 arranged on a horizontal shaft 28 located vertically below the molding devices and operable through the medium of a lever 29. This shaft may also have a yoked member 30 guided thereon through the medium of slots 31, the yoke member straddling the cam 27 which moves the said yoke member in opposite directions on the shaft 28. In the yoke member 30, a screw rod 32 is journaled to turn, said rod having its screw portion 33 coöoperating with a slide or nut 34 which extends through a slot in the top of the frame portion 1 and is resiliently connected to the carriage 25, preferably by means of a rod 35 surrounded by a spring 36 and adjustably secured to the carriage 25. The screw rod 32 provides an adjustment in the operating means for accommodating the latter to lasts of different lengths and is preferably turned by a hand piece 37 arranged at one end of the frame portion 1. The elastic connection between the operating means and the carriage 25 is provided in order that the pressure of the last against the molding devices may be resilient or yielding. It is apparent that the movement of the lever 29 moves the last toward and from the molding devices in a horizontal plane parallel with the plane of yielding or movement of the molding devices, the last being accommodated within the recessed portion 22 as it approaches and engages the molding devices.

With the end in view of supporting or pressing the bottom of the last and the upper thereon against the surfaces 5 and 6 of the flanged portions of the molding devices, means is provided for exerting an upward pressure against the toe portion of the last. In this instance, an engaging member 38 is employed which is preferably covered with a yielding material or pad 39 to prevent injury to the upper on the last. This engaging device may be adjustably ar-

ranged on a rod or vertically movable member 40 which near its upper end is guided through a collar 41, the latter in turn being resiliently or yieldingly supported for slight lateral movement and to this end carrying a horizontally extending stem 42 guided in a perforated lug 43 and pressed in one direction by a coil spring 44 which surrounds the stem and abuts at one end against the collar 41 and at the other end against the lug 43. This supporting rod 40 may also be operated by the cam 27, and, to this end, it carries at its lower end a yoke 45 which straddles the shaft 28 to be guided vertically by the latter and also straddles the cam 27 in order that the said cam may engage the yoke 45 to lift the engaging device 38 after the said cam engages the yoke 30 to shift the last 23 toward the molding devices. A spring 46 surrounds the rod 40 between the yoke 45 and the collar 41 and acts to depress the engaging device 38 and the rod 40 after the last has been moved away from the molding devices.

25 The operation of the invention will be understood from the foregoing description but the contemplated manner of using the illustrative machine may be summarized as follows: A lasted shoe while still on the last is placed in an inverted position upon the adjustable support 24 so that the toe points toward the molding devices, the parts being adjusted, of course, to the size of the shoe on which the machine is to operate.

30 By operating the lever 29, the last and the shoe are forced against the molding devices and particularly against the faces 4 thereof near the abutting ends of the molding devices. This causes the latter to rock on their pivots 8 which also shift to permit the molding devices to conform to the shape of the toe. After a certain pressure has been exerted upon the parts, the engaging member 38 moves upwardly to

35 force the underlapping stock of the upper against the face 6 and the face 5 of the flange. The molding devices are preferably heated to a sufficiently high degree to cause the leather to shrink and become set, so

40 that, as the pressure is exerted simultaneously upon the whole end of the shoe, including the turn or bend at the sole edge line and on opposite sides of the latter, the toe is molded into the shape of the molding

45 devices which also conform to the shape of the last. This treatment of the shoe removes from the portions of the toe which will be exposed to view in the completed shoe the wrinkles, plaits, or crimps which are occasioned by or formed in turning the upper

50 inwardly at and adjacent to the sole edge line. The described mounting for the molding devices, by which they are conformable to the shoe, is applicable to the end embracing plates or wipers used in lasting

55

shoes, and the shoe presenting means is adapted for use in lasting machines, and it is intended that the claims to these portions of the invention shall be construed to afford such protection for their use in lasting machines as the state of the lasting machine art justifies.

The illustrated machine has been designed more particularly for molding the toes of McKay shoes and welt shoes. By reducing the size of the flanges on the molding devices, the same machine may be employed for molding the toes of "turn" shoes. It is apparent also that the machine may be adapted for molding the heel portions of shoes, and such a heel portion molding machine has particular advantages when used with a "turn" shoe as it tends to give a definite form to the heel counter, it being well known that heel counters of "turn" shoes cannot be molded before being inserted in the shoes as is usually done in the manufacture of McKay shoes and in the manufacture of many welt shoes.

The invention is illustrated as used in shaping the toe end of a McKay shoe after it has been lasted and while the upper material is secured in lasted position. In Fig. 8 is shown the condition of a lasted McKay shoe at the toe end before treatment by the machine of the present invention, while Figs. 9 and 10 show the condition of the toe after being operated upon by such machine. From these illustrations it will be seen that the end of the shoe is given the desired shape and that all crimps or wrinkles are eliminated from the bend or sole edge line and also from those portions of the upper upon opposite sides of the bend or sole edge line. A further advantage from use of the invention on a McKay shoe is that the shoe is in a better condition to receive the outer sole, as the latter may lie flat against the underlapping stock of the upper in proximity to the sole edge line so that no space is provided between the shoe upper and the lower or outer sole.

The method of shaping or molding the ends of boots and shoes herein disclosed is not claimed in this application, but is claimed in divisional application, Serial No. 19,693, filed April 7, 1915.

What I claim as my invention and desire to secure by Letters Patent is:

1. In a shoe molding machine, the combination with means for supporting a last and the shoe thereon, of molding means adaptable to conform to the shape of the shoe as determined by the last, and means for heating said molding means.

2. In a shoe molding machine, the combination with a support for the shoe, of two molding devices having abutting ends adapted to rock one upon the other, swinging links pivoted to the molding devices at

points between the ends thereof, and yielding means acting on the molding devices to hold their abutting ends in engagement.

3. In a shoe molding machine, the combination with a support for the shoe, of two molding devices having abutting ends each adapted to rock upon the other, links each pivoted at one end to swing and having the other end pivoted to a molding device between the ends of the latter to provide a shiftable pivot for such molding device, and a spring-pressed member having rollers engaging both molding devices near the abutting ends to swing the other ends of the molding devices outwardly and to permit the abutting ends to yield when engaged by a shoe so as to conform to the shape of a portion of the shoe.

4. In a shoe molding machine, the combination with a frame having two parallel guides, of two molding devices having abutting ends each adapted to rock upon the other, said molding devices being arranged between said guides, two links each pivoted at one end and having the other end pivoted to one of the molding devices between the ends of the latter, and a spring-pressed yoke member also operating between the guides and having rollers bearing against the molding devices near the abutting ends of the latter.

5. In a shoe molding machine, the combination with a support for a lasted shoe, of molding means embodying a plurality of relatively movable molding devices conformable to the shape of a portion of the lasted shoe, and heating means for such molding devices.

6. In a shoe molding machine, the combination with a support for a lasted shoe, of molding means embodying a plurality of relatively movable molding devices arranged to conform to the shape of a portion of the shoe, a plate arranged in contact with said molding devices, and means for heating said plate.

7. In a shoe molding machine, the combination with toe molding means embodying a plurality of molding devices arranged to conform to the shape of the toe of a lasted shoe, of last supporting means, said toe molding means and last supporting means being relatively movable to effect the engagement of the toe molding means with the toe of a shoe on the last supporting means.

8. In a shoe molding machine, the combination with a last supporting means, of toe molding means embodying a molding device having two faces at angles to each other and a concaved face connecting them, means for forcing together the toe molding means and a last on the last supporting means to cause one of said faces to bear with pressure against the toe of a shoe on the last, and means for moving the last transversely of

the first mentioned line of movement to cause the toe of the upper to bear with pressure against the other face and the concaved face.

9. In a shoe molding machine, the combination with a last supporting means, of a toe molding means embodying relatively movable molding devices having two faces at angles to each other and a concaved face connecting them, means for moving the last supporting means to cause the toe of the last to coöperate with one of the faces of each molding device, and means for coöperating with the toe of the last to move the latter laterally of the first line of movement to cause the toe of the shoe to bear with pressure against the concaved face and the other face of the molding device.

10. In a shoe molding machine, the combination with a last supporting means, of toe molding means embodying relatively movable molding devices adapted to conform to the shape of the toe and having two faces at angles to each other and a concaved face connecting them, means for coöperating with the toe of the last to shift the latter laterally against the concaved face and the other face of each of the molding devices, and a common operating member for moving the last supporting means toward and from the toe molding means and also for operating the last-toe shifting means.

11. In a shoe molding machine, the combination with a last supporting means, of toe molding means having two faces at angles to each other and a concaved face connecting them, means for shifting the last-toe to cause the toe of the shoe to engage one of the faces and the concaved face, a common operating member for moving the last supporting means toward the toe molding means and for operating the last-toe shifting means, and resilient means interposed between the last supporting means and the common operating member to adapt the machine to inequalities in the shoes.

12. In a shoe molding machine, the combination with a last supporting means, of toe molding means embodying a molding device having two faces at angles to each other and a concaved face connecting them, last-toe shifting means for moving the toe of a shoe on the last against one of said faces and also against the concaved face of the molding device, a common operating member for moving the last-toe shifting means and for moving the last supporting means toward the toe molding means, and an adjustable connection interposed between the last supporting means and the common operating member, permitting the machine to be adapted to lasts of different sizes.

13. In a shoe molding machine, the combination with a last supporting means, of molding means for coöperating with an

upper on a last supported on the last supporting means, a carriage by which said last supporting means may be moved toward and from the toe molding means, a nut connected to the carriage, a cam shaft having a cam thereon, a yoke guided on the cam shaft and moved back and forth by the cam, and a screw rod mounted to turn in the nut and also in the yoke and forming a connection between the yoke and the nut, whereby the carriage may be moved back and forth by the cam on the cam shaft.

14. In a shoe molding machine, the combination with a frame having an upright portion and a horizontally extending portion, of molding means carried by the upright portion, a carriage guided on the horizontal portion to move toward and from the molding means, and last supporting means arranged on said carriage.

15. In a shoe molding machine, the combination with a frame having molding means arranged thereon and adapted to conform to a portion of the shoe on the last, of a carriage movable on said frame toward and from the molding means, and a pin adjustable on said carriage for supporting the last in an inverted position for coöperation with the molding means.

16. In a shoe molding machine, the combination with a frame having an upright portion provided with molding means and a horizontal portion provided with a guide, of a carriage movable toward and from the molding means on said guide, a last supported by the carriage for supporting an upper to be engaged by the molding means, a nut connected with the carriage, a cam shaft having a cam thereon, a yoke guided on the cam shaft, and a screw rod turning in the yoke and operating in the nut to form an adjustable connection between the yoke and the carriage.

17. In a shoe molding machine, the combination with a last supporting means, of toe molding means, means for effecting a relative movement between the last supporting means and the toe molding means, and a last toe shifter for causing pressure between the toe molding means and the toe of an upper on the last of the last supporting means.

18. In a shoe molding machine, the combination with a last supporting means, of toe molding means, means for effecting a relative movement between the last supporting means and the toe molding means, and a last toe shifter for causing pressure between the toe molding means and the toe of an upper on the last of the last supporting means, said last toe shifter having a yielding surface for coöperation with the upper on the last and being laterally movable to prevent a rubbing action on the upper.

19. In a shoe molding machine, the combination with a last supporting means, of toe molding means, means for effecting a relative movement between the last supporting means and the toe molding means, and a last toe shifter for causing pressure between the toe molding means and the toe of an upper on the last of the last supporting means, said last toe shifter comprising a yielding surface for coöperation with the upper on the last and a laterally movable and also longitudinally movable rod by which said yielding surface is carried.

20. In a machine for shaping the end portion of a shoe after it has been lasted and while the upper is secured in lasted position, the combination of a support to sustain the lasted shoe, of molding means adaptable to conform to the shape of the last at one end of the shoe, and pressure transmitting means for causing the lasted end portion of the shoe to be subjected to a shaping pressure by said means to reshape the leather around the end of the last while it is held in lasted position.

21. In a machine for shaping the end portion of a shoe subsequent to lasting, the combination of a support to sustain the lasted shoe, of means to shape the lasted shoe at one end thereof, devices for relatively moving the shoe and said means to project the said means over the lasted shoe above the sole edge line, and means for transmitting pressure through the shaping means in a direction transverse to said relative movement for causing the leather at the end portion of the lasted shoe to be subjected to a shaping action by said shaping means.

22. In a machine for molding the end portion of a shoe after it has been lasted, the combination of a last support to sustain the lasted shoe, of molding means for co-operating with the shoe on the last support and adapted to conform to the shape of the lasted shoe at one end thereof, said molding means having two portions for coöperating with the end portion of the shoe on opposite sides of the sole edge line, and means for subjecting the end of the lasted shoe to pressure by the molding means.

23. In a shoe molding machine for molding the end portion of a shoe after it has been lasted and while the upper is secured in lasted position, the combination of a support to sustain the lasted shoe, of molding means conformable to the shape of the lasted shoe at one end thereof, and means for heating the lasted shoe while subjected to the action of the molding means.

24. In a machine for molding and reshaping the end of a shoe after it has been lasted, the combination of a support to sustain the lasted shoe, of molding means conformable with one end of the lasted shoe and having two relatively fixed portions for acting

upon the lasted shoe on opposite sides of the sole edge line, and means for heating the molding means.

25. In a machine for molding and reshaping the end portion of a shoe after it has been lasted and while the upper is secured in lasted position, the combination of supporting means for sustaining the lasted shoe, of molding means conformable with 10 the lasted end of the shoe and having a por-

tion adapted to engage the lasted shoe above the sole edge line, and means for relatively moving the lasted shoe and molding means to project the latter over the lasted shoe above the sole edge line.
